ATTORNEYS.

UNITED STATES PATENT OFFICE.

TIMOTHY F. CROWLEY, OF BROOKLYN, NEW YORK.

BLADE HOLDER.

Application filed September 22, 1926. Serial No. 136,959.

This invention relates to a blade holder which is suitable for clamping any type of safety razor blade and to position it at any angle relative to the handle.

- 5 The invention is designed to provide the handle with a slotted or slotted portion, the bifurcation of which is resilient in order to draw the sections together thus securely holding the blade in a fixed position.
- 10 An object of the invention is to provide a simple and inexpensive holder in which the blade can be easily adjusted to any desired angle and when not in use can be moved into the slot in the handle thereby sheathing the 15 cutting edges of the blade.

The invention resides more particularly in the novel combinations hereinafter described and claimed, reference being made to the accompanying drawing in which:—

- 20 Fig. 1 represents a front elevation of a holder embodying this invention.

Fig. 2 is a side view of the same.

Fig. 3 is a view like Fig. 1 showing a different blade clamped in the holder.

- 25 Fig. 4 is a section taken along the line 4 4 of Fig. 1.

Fig. 5 is a section taken along the line 5 5 of the same.

- 30 Fig. 6 is a vertical section taken along the line 6 6 of Fig. 3.

The holder consists of a cylindrical handle 5 preferably made of wood and having reinforcing caps 6 of metal each respectively fixed to its upper and lower end. The handle has a 35 slotted or slotted portion 7 extending from its upper end longitudinally into the handle thereby dividing the handle adjacent the slot into two sections. The branches of the section are springy so that they can be forced toward each other or spring apart within certain limits.

- 40 A hole 8 near the upper end of the branches and located at right angles to the slot is provided for the insertion of a bolt 9 having a threaded end. The bolt includes a finger member 10 fixed to one end and a wing nut 11 engages the threaded opposite end of the bolt.

45 As indicated in Figs. 1 and 2 a Gillette blade 12 is mounted on the bolt which passes through one of its holes 14 and the cutting edge is arranged parallel with the handle. By tightening the wing nut, it forces the branch sections together thereby clamping the blade therebetween. When it is desired to 55 sheathe the blade as indicated in dotted lines in Fig. 1 the wing nut is loosened springing

the sections away from each other, then turning the blade about the bolt to set it in the slot. It will be seen that the diameter of the handle is sufficient to cover the cutting edges 60 so that they will not protrude and accidentally cut a person. The blade can readily be swung out of the handle to the position shown by fingering the edge projecting above the cap and in this position it can be used to cut any 65 number of articles but if desired it could be placed at right angles to the handle and used for scraping paint or other purposes.

As shown in Fig. 3, the upper end of the handle is provided with an Eveready blade 70 but, of course, any other make of blade with or without holes could be positioned in the same way. In this method of arranging the blade, the bolt is adapted to form a stop and the sections above the bolt clamp the 75 blade when at right angles to the axis of the handle. When the blade is arranged parallel with the handle as indicated in dotted lines it can be clamped between the two sections extending above and below the bolt. 80 In this way any type of razor blade can be moved and fixed in almost any position relative to the handle and used for multitudinous purposes.

The holder can be carried in a person's 85 pocket and in order to prevent the blade from moving out of the holder when it is housed in the slot, a spring catch bolt 15 arranged below the screw bolt is provided. The bolt by the action of the spring impinges onto the surface of the blade so as to force it against the wall of the slot.

I claim:—

1. A blade holder comprising a handle having a slot extending from the upper end into the handle for receiving and sheathing a safety razor blade, a screw bolt coaxing with the upper end of the slot, and a spring actuated catch bolt made to impinge onto the blade when sheathed.

2. In combination a safety razor blade of the ordinary perforated type with arcuate ends, and a blade holder comprising a handle having resilient blade holding arms, a recess in the handle defined by said resilient arms for sheathing the blade in closed position, and a screw bolt passing through the resilient arms and through a perforation of the blade and located closer to the end of the handle than to the corresponding end of the 110 blade whereby when the blade is in closed position one arcuate end thereof projects be-

yond the end of the handle providing a manipulating means for the blade.

3. A blade holder for razor blades of the ordinary perforated type having arcuate ends comprising a handle having resilient arms with a blade sheathing space between them, and adjusting means engaging the arms and one of the perforations of the blade for pressing said arms on said blade 10 to hold it in a predetermined position, said adjusting means being located closer to the end of the arms than to the corresponding end of the blade whereby when the said blade is in sheathed position one arcuate end projects beyond the ends of the arms thereby providing and manipulating means 15 for the blade.

4. In combination a safety razor blade of the ordinary perforated type with arcuate 20 ends, and a blade holder comprising a handle having resilient blade holding arms; a space in the handle defined by said resilient arms for sheathing the blade in closed position, a screw bolt passing through the resilient arms and through a perforation of the 25 blade and located closer to the end of the

handle than to the corresponding end of the blade whereby when the blade is in closed position one arcuate end thereof projects beyond the end of the handle providing a 30 manipulating means for the blade, and a spring actuated catch bolt made to impinge onto the blade when sheathed.

5. A blade holder for razor blades of the ordinary perforated type having arcuate 35 ends comprising a handle having resilient arms with a blade sheathing space between them, adjusting means engaging the arms and one of the perforations of the blade for pressing said arms on said blade to hold it 40 in a predetermined position, said adjusting means being located closer to the end of the arms than to the corresponding end of the blade whereby when the said blade is in sheathed position one arcuate end projects 45 beyond the ends of the arms thereby providing a manipulating means for the blade, and a spring actuated catch bolt made to impinge onto the blade when sheathed.

In testimony whereof I have hereunto set 50 my hand.

TIMOTHY F. CROWLEY.
